(57) **CLAIM**

The ornamental design of a hand-held mixer for flowable materials, as shown and described.

DESCRIPTION

FIG. 1 is a perspective view of a hand-held mixer for flowable materials incorporating my new design.

FIG. 2 is a top plan view thereof;

FIG. 3 is a bottom plan view thereof;

FIG. 4 is a front elevational view thereof;

FIG. 5 is a rear elevational view thereof; and,

FIG. 6 is a right side view thereof, with the left side being a mirror image of the right side view.
